UNITED STATES PATENT OFFICE

FRITZ LUDWIG HERMAN AMBERGER, OF NEW YORK, N. Y., ASSIGNOR TO HOLEPROOF
HOSIERY CO., OF MILWAUKEE, WISCONSIN, A CORPORATION

DESIGN FOR AN ADVERTISING ORNAMENT

Application filed April 7, 1933. Serial No. 47,719. Term of patent 7 years.

To all whom it may concern:

Be it known that I, FRITZ LUDWIG HERMAN AMBERGER, a citizen of Switzerland, residing at New York, in the county of New York and State of New York, have invented a new, original, and ornamental Design for an Advertising Ornament, of which the following is a specification, reference being had to the accompanying drawing, forming part thereof.

The figure is a perspective view of the advertising ornament showing my new design.

I claim:

The ornamental design for an advertising ornament as shown.

In testimony whereof I affix my signature.

FRITZ LUDWIG HERMAN AMBERGER.
